United States Patent Office.

E. A. GOODES, OF PHILADELPHIA, PENNSYLVANIA, ASSIGNEE TO FRANCIS M. WOOD,
HENRY F. HAYS, SAMUEL ALLEN, JOSEPH S. BROWN, THEODORE E. WEIDER-
SHIEM, AND THOMAS S. KEYSER, OF SAME PLACE.

Letters Patent No. 96,221, dated October 26, 1869.

IMPROVED TREADLE-MOTION.

The Schedule referred to in these Letters Patent and making part of the same.

To all whom it may concern:

Be it known that I, E. A. GOODES, of Philadelphia, in the county of Philadelphia, and State of Pennsylvania, have invented a new and improved Treadle-Motion; and I do hereby declare that the following is a full, clear, and exact description thereof, which will enable others skilled in the art to make and use the same, reference being had to the accompanying drawings, forming part of this specification.

This invention relates to improvements in treadle-motions for sewing-machines, foot-lathes, and other light machinery, and has for its object to provide an improved arrangement whereby the power may be applied by a to-and-fro swinging motion of the foot.

The invention consists of a disk, or other equivalent device, connected to the lower end of a vibrating pendulum, so as to vibrate thereon, and to which, at the top, the crank connecting-rod is jointed, and all arranged in such a way that the lower face of the disk being prevented from swinging, an oscillating motion imparted to the axis will swing the top back and forth, so as to impart rotary motion to the crank, as herein-after more fully specified.

Figure 1 represents a side elevation of my improved treadle-motion, and

Figure 2 is a diagram, showing the positions of the different parts at the different stages of the movements.

Similar letters of reference indicate corresponding parts.

A is a pendulum, suspended by a pivot-joint from the under side of the table, or a bracket, or other support attached to the same.

B is a heavy disk, or other suitable device, suspended from the lower end by a pin or bolt, C, passing through its centre of gravity, and on which a foot-board, D, is secured.

This disk B is slotted or otherwise arranged at the

bottom for connection to any fixed rod or stud, E, to hold it against swinging with the pendulum.

The pitman-rod F is connected to this disk at the top by a wrist-pin, and to the wrist-pin of the crank G. By placing the foot on the foot-board D, and swinging the pendulum forward and back, the disk B will be caused, by reason of being held at the bottom, to oscillate on its centre C, so as to impart a to-and-fro motion to the rod F, for working the crank-shaft through the crank G.

The diameter of the disk should be about twice the length of the crank, but it may be varied, as may be found best in practice.

It is not essential that the part B should be in the form of a disk, as any other shape, which will accomplish the object by oscillating on the axis C, and which will support the connecting-rod on one side, while the other is held from oscillating, will do as well. The connecting-rod may be at the bottom and the holding-device at the top if preferred.

The vertical line a, in fig. 2, represents the position of the pendulum when the device is standing, and the lines b c, on each side the positions, when the crank is passing the centres, whereby it will be seen that the crank will always be in the best position for starting by the action of the feet on the treadle, without the aid commonly required in other arrangements of the hands to turn the cranks past the centres.

Having thus described my invention,
I claim as new, and desire to secure by Letters Patent—

The combination of the pendulum A, disk B, or its equivalent, pivot-bolt C, treadle D, connecting-rod F, and a holding-device, E, substantially as specified.

E. A. GOODES.
